Application February 21, 1958, Serial No. 716,706

Claims priority, application Germany February 22, 1957

8 Claims. (Cl. 51—141)

The present invention relates to platen grinding and polishing machines, and more particularly to platen means for platen grinding and polishing machines.

Machines of this type are equipped with an endless abrasive belt traveling over the work at considerable speed. The belt is guided in a closed path by guide pulleys and is supported in the working zone by a pressure platen of metallic or non-metallic material which may be equipped with a resilient surface coating or cover.

Platens for belt grinding and polishing machines of a known type are equipped with pneumatic chambers which permit adjustment of the pressure exerted by the abrasive belt on the work piece. Provisions are made for raising the pneumatic chambers from the side of the machine opposite the feed end in order to prevent damage to the trailing edge of the work piece.

Another known type of belt grinding machines is equipped with a plurality of air-actuated grinding shoes which press the abrasive belt against the work piece. In other belt grinding machines, a platen swings in an oscillating movement over the entire width of the work table in order to provide uniform grinding pressure independent of the skill of the operator.

Because of the large contact area between pressure platen and abrasive belt, the belt temperature is increased substantially which leads to rapid wear of the abrasive belt.

Because of the uniform application of pressure over the entire area of contact between the work piece and the abrasive belt, the grinding dust cannot escape from the working zone with sufficient speed. This again leads to overheating of the work and of the belt in the work zone and results in an uneven grinding effect.

An object of the present invention is the provision of platen means which permit grinding or polishing of a flat surface to the very edge without damaging said edge.

Another object is to provide such platen means which reduce heating of the work piece and of the belt.

A further object of the invention is the provision of a platen means for grinding and polishing machines which reduces the area of maximum contact pressure.

Still another object of the invention is the provision of pressure platen means which permit the escape of grinding dust from the work zone thus giving a cleaner and more uniform grinding or polishing effect.

Other objects and advantages of the invention will hereafter become more fully apparent from the following description of the annexed drawings which illustrate a preferred embodiment, and wherein:

Fig. 1 is a plan view of a preferred embodiment of the stationary back-up belt of the invention.

Fig. 2 is an elevational view of a belt grinding machine equipped with the back-up belt of the invention, and

Fig. 3 is an enlarged detail view of the device of Fig. 2. Referring now to the drawings, wherein like reference

2

numerals designate like or corresponding parts throughout the several views, there is shown a work table 1 reciprocably movable in a horizontal plane at right angle to the direction of movement of an abrasive belt 10, a rigid backing platen 2, having mounted thereon a resilient surface cover 3 of relatively soft cushioning material, such as sponge rubber, which presses in the working zone against an endless steel belt 4 looped around guide pulleys 5 and 6 and held in a longitudinally adjustable fixed position by said guide pulleys. A portion of steel belt 4 is provided with a cover 7 of cleat-like projections holding the endless abrasive belt 10 in contact with the workpiece 13. Belt 10 is looped around guide pulleys 11 and 12 at least one of which is driven in the conventional manner by an electric motor or other prime mover whereby the abrasive belt 10 may be made to travel over the workpiece in the direction of the arrow shown in Fig. 2 at high speed. The position of belt 4 on pulleys 5 and 6 is arranged in such a manner that the end of the cleat cover 7 coincides precisely with the leading edge 13' of the work piece which is to be ground or polished by abrasive belt 10. Work piece 13 is held in proper alignment on work table 1 by a guide stop 14 and is worked upon by abrasive belt 10. Belt 10 is backed up by platen means including a steel belt 4 with cleat cover 7 adjustable as indicated by the arrow in Fig. 3, for precise alignment of the leading edge 13' of work piece 13 with the limit 7' of the cleat cover 7.

The above described device operates as follows:

Steel belt 4 has a canvas cover 8, ridge-shaped projections 7" of elastic material such as leather cleats, fastened to steel belt 4 by means of rivets 9 which pass through the intermediate canvas cover. Longitudinal rows of spaced cleats are arranged along the edges of belt 4. The surface of belt 4 between the edges is provided with rows of spaced cleats arranged at an angle to the rows at the edges. The canvas cover 8 and cleats 7" cover only a portion of steel belt 4 and end abruptly along a straight limit line 7' transverse to the longitudinal direction of belt 4.

A work piece is fastened to the work table 1 and stop 14 is adjusted so that the edge 13' of the work piece is exactly at right angle to the plane of rotation of abrasive belt 10 and parallel to the direction of travel of work table 1. Pulleys 5 and 6 are then rotated and belt 4 shifted thereby until the cleat cover 7 of belt 4 extends across the entire width of the work piece 13 and the limit 7' of the cleat cover is precisely aligned with the leading edge 13' of the work piece. The position of belt 4 is fixed by suitably arresting pulleys 5 or 6. The motor actuating movement of the abrasive belt 10 is started and the work piece is passed under the belt for grinding or polishing in the usual manner. If necessary, the position of belt 4 may again be adjusted by means of pulleys 5 and 6 while the machine is running.

It is apparent that the area of pressure is precisely limited at the edge 13' of work piece 13 and that damage to the leading edge 13', that is, the edge exposed to the attack of the abrasive belt, which is a serious shortcoming of many types of platen grinding machines, is avoided or held to a minimum. The provision of individual ridge shaped elements or cleats backing up the abrasive belt reduces the area of maximum pressure between the belt and the work piece, thus reducing belt wear, avoiding excessive heating of belt and work, and permitting the accumulated grinding dust to escape. The steel belt 4 on which cleats 7" are mounted has been found to increase the useful life of the cleat cover 7 which is subject to shear forces by contact with the rapidly moving abrasive belt.

While a sponge rubber cushion 3, a steel belt 4, and

leather cleats 7" have been shown in the preferred embodiment illustrated, it will be understood by those skilled in the art that such materials were mentioned as illustrative only and that a wide variety of metallic and non-metallic materials will lend itself to application in the stationary belt of the invention, that a sponge rubber cushion on the rigid backing platen may be omitted or replaced by other material having more or less resilience than sponge rubber, and that the choice of suitable materials for the cleats or projections with which the surface of the stationary belt is equipped is very wide and depends among other things on the magnitude of the pressure that is to be transmitted by the projections, on the backing material of the abrasive belt and on its speed.

It should be understood, of course, that the foregoing disclosure relates to only a preferred embodiment of the invention and that it is intended to cover all changes and modifications of the example of the invention herein chosen for the purpose of the disclosure, which do not constitute departures from the spirit and scope of the invention set forth on the appended claims.

What is claimed is:

1. In an abrasive grinding machine having a work face adapted to support and position a workpiece, an abrasive belt operably disposed opposite said work face, a backing belt mounted within and stationary with respect to said abrasive belt, rigid backing means positioned in contact with the inner side of said backing belt, and a plurality of projections regularly disposed over a portion of the outer side of said backing belt, the construction and arrangement being such that the leading edge of the workpiece coincides with the leading edge of said spaced projections.

2. An abrasive grinding machine comprising a work face adapted to support and position a workpiece, an abrasive belt operably disposed opposite said work face, a backing belt mounted within and stationary with respect

to said abrasive belt, rigid backing means positioned in contact with the inner side of said backing belt, and a plurality of projections covering a portion of the outer side of said backing belt, the construction and arrangement being such that the leading edge of the workpiece coincides with the leading edge of said projections.

5 3. An abrasive grinding machine as in claim 2, further comprising a resilient surface cover disposed between said rigid backing means and said backing belt and secured to said rigid backing means.

10 4. An abrasive grinding machine as in claim 2 wherein said projections have an elongated shape.

15 5. An abrasive grinding machine as in claim 2, wherein said projections are regularly arranged on said backing belt in angular rows oblique to the edge of said back-up belt.

20 6. An abrasive grinding machine as in claim 2, wherein said projections are disposed to form a plurality of flat surfaces parallel to the lower surface of said back-up belt.

7. An abrasive grinding machine as in claim 2, wherein said projections have substantially parallel edges.

25 8. An abrasive grinding machine as in claim 2, wherein said projections are arranged in rows, two of said rows being adjacent and parallel to the respective edges of said back up belt, and the remaining rows being obliquely disposed to said edges.
